Primary Examiner—Stella M Reid*Assistant Examiner*—Elizabeth J Oswecki(74) Attorney, Agent, or Firm—Hughes Hubbard & Reed LLP; Ronald Abramson; Peter A. Sullivan(57) CLAIM

The ornamental design for a bottle, as shown and described.

DESCRIPTION

FIG. 1 is a perspective view of a bottle showing my new design;

FIG. 2 is a front view thereof;

FIG. 3 is a right side view thereof;

FIG. 4 is a left side view thereof;

FIG. 5 is a top view thereof; and,

FIG. 6 is a bottom view thereof.

All sides not shown form no part of the claimed design

The broken line showing of the bottom view in FIG. 6 is included for the purpose of illustrating only and forms no part of the claimed design.
